UNITED STATES PATENT OFFICE.

JOHN K. CLARK, OF BUFFALO, NEW YORK.

SPRING-HINGE.

SPECIFICATION forming part of Letters Patent No. 276,000, dated April 17, 1883.

Application filed February 6, 1883. (Model.)

To all whom it may concern:

Be it known that I, JOHN K. CLARK, a citizen of the United States, residing at Buffalo, in the county of Erie and State of New York, 5 have invented new and useful Improvements in Spring-Hinges, of which the following is a specification.

This invention relates to improvements in that class of spring-hinges which are composed 10 of two leaves, each having top and bottom eyed lugs, through which passes a connecting-pintle, a coiled spring encircling the pintle between the said lugs and secured at one end to a collar for engaging a device on one of the 15 hinge-leaves in such manner that the collar can be rotated to adjust or vary the tension of the spring and then be locked in its adjusted position.

The object of my invention is to provide 20 novel and efficient means for engaging the collar to lock it when adjusted; and to this end I provide a swinging device which is loosely supported by an arm or stud projecting from a ring or equivalent contrivance, whereby rivets are rendered unnecessary to form a bearing 25 for the locking device to swing upon, and all parts comprising the hinge, except the spring, can be cast complete without resorting to drilling and fitting, thus materially reducing the 30 cost of manufacturing those hinges of the character alluded to, which are provided with swinging hooks to lock the tension-adjusting collar.

The manner of carrying out my invention is 35 illustrated in the accompanying drawings, in which Figure 1 represents a plan view, looking at the front of a hinge provided with my invention; Fig. 2, a perspective view of the several parts detached; Fig. 3, a plan view, 40 looking at the rear of the hinge; and Fig. 4, a detached enlarged view of the swinging locking device and its support.

In order to enable others skilled in the art to make and use my invention, I will now proceed to describe the same in detail, reference being had to the accompanying drawings, wherein—

The numerals 1 indicate the leaves of the hinge; 2, the top and bottom eyed lugs; and 45 3, the connecting-pintle; 4, the coiled spring, having its lower end seated in a cup-shaped collar, arranged to turn with one of the leaves,

and its other end arranged in a cup-shaped recess in a notched collar, 5, which constitutes a tension-adjusting device for the spring. 55

The parts referred to are in substance the same as spring-hinges heretofore constructed.

The notched collar or equivalent tension adjuster is adapted to be rotated for the purpose of changing or varying the tension of the spring, 60 and when the collar is adjusted to secure the requisite tension it is locked in such position by a swinging hook, lever-latch, or similar device, adapted to engage the same. To support this swinging locking device without the necessity 65 of arranging it on a separate pin or projection, which must be riveted to one of the hinge-leaves, I loosely support or suspend such device in a seat, 7, provided in an arm, 8, formed on a ring or other contrivance, which is secured in place by the pintle of the hinge passing through it. As here shown a ring is located between the two top eyed lugs of the 70 respective hinge-leaves, and constitutes an intervening washer, which subserves the function of sustaining the locking device for the 75 tension-adjusting collar.

The collar-locking device 6 consists in the present example of a right-angled plate of cast metal, one arm being adapted to engage any 80 of the notches in the tension-adjusting collar, and provided with a finger-piece, 9, for retracting or disengaging it from the collar, while the other arm is provided at its end with a curved projection, 10, the curved part resting 85 in the seat 7, which is correspondingly curved, thus providing an accurate bearing on which the locking device can rock or swing to engage and disengage the notched collar.

In order to prevent the ring from turning on 90 the pintle, and thereby disengage the locking device from the tension-adjusting collar, I provide the rear portion of the ring with a lateral projection or shoulder, 11, which rests against an abutment, 12, formed by one wall 95 of a recess in the rear side of one of the hinge-leaves. The abutment for the rear projection or shoulder of the ring could be otherwise constructed—as, for example, it could be formed by a lug projecting from the hinge-leaf; but the recess illustrated is the most desirable in that it brings the rear of the ring flush with the rear surface of the hinge-leaf.

The several devices composing the hinge,

except the coiled spring, are cast complete, and in arranging them together for use no drilling or fitting is essential. Hence, it will be obvious that the hinge can be manufactured at less cost than those hinges of a somewhat similar character in which the swinging locking device is hung on a pivot riveted to one of the hinge-leaves.

I do not confine myself to the particular form of locking device, tension-adjusting collar, and ring interposed between the eyed lugs as herein shown, for the reason that so far as I am aware no tension-adjusting collar has been locked and unlocked by a swinging device suspended from a ring or equivalent contrivance without the necessity of riveting the bearing or pivot of the swinging locking device to some part of the hinge-leaf, which of course necessitates drilling the hinge-leaf to receive the bearing or pivot.

Having thus described my invention, what I claim is—

1. The combination, with a spring and a tension-adjusting collar therefor, of a movable locking device loosely supported by an arm or stud on a ring, substantially as described.

2. A ring interposed between the eyed lugs of a spring-hinge, and from which is suspended a swinging device for engaging the tension-adjusting collar of the hinge-spring, substantially as described.

In testimony whereof I have hereunto set my hand in the presence of two subscribing witnesses.

JOHN K. CLARK.
